UNITED STATES PATENT OFFICE

158,475

PORTABLE SPINNING AND TWISTING MACHINE

Willard C. Lamoreaux, Norwalk, Conn.

Application September 15, 1948, Serial No. 148,593

Term of patent 3½ years

(Cl. D92—15)

To all whom it may concern:

Be it known that I, Willard C. Lamoreaux, a citizen of the United States, residing at Norwalk, county of Fairfield, and State of Connecticut, have invented a new, original, and ornamental Design for a Portable Spinning and Twisting Machine, of which the following is a specification, reference being had to the accompanying drawings, forming part thereof.

Figure 1 is a top view of a portable spinning and twisting machine, showing my new design.

Fig. 2 is a side view of the same.

Fig. 3 is a front view of the same.

I claim:

The ornamental design for a portable spinning and twisting machine, as shown.

WILLARD C. LAMOREAUX.
